(57) **CLAIM**

The ornamental design for massage chairs with display device, as shown and described.

DESCRIPTION

FIG. 1 is a front right perspective view of a first embodiment of massage chairs with display device;

FIG. 2 is a front view of massage chairs with display device of FIG. 1;

FIG. 3 is a rear view of massage chairs with display device of FIG. 1;

FIG. 4 is a left side view of massage chairs with display device of FIG. 1;

FIG. 5 is a right side view of massage chairs with display device of FIG. 1;

FIG. 6 is a top view of massage chairs with display device of FIG. 1;

FIG. 7 is a bottom view of massage chairs with display device of FIG. 1;

FIG. 8 is a front right perspective view of a second embodiment of massage chairs with display device;

FIG. 9 is a front view of massage chairs with display device of FIG. 8;

FIG. 10 is a rear view of massage chairs with display device of FIG. 8;

FIG. 11 is a left side view of massage chairs with display device of FIG. 8;

FIG. 12 is a right side view of massage chairs with display device of FIG. 8;

FIG. 13 is a top view of massage chairs with display device of FIG. 8; and,

FIG. 14 is a bottom view of massage chairs with display device of FIG. 8.

The stipple shading is used to indicate wood panels. The broken lines in the drawings illustrate portions of the article that form no part of the claimed design.

1 Claim, 14 Drawing Sheets
